UNITED STATES PATENT OFFICE.

OMER C. GOULET, OF FALL RIVER, MASSACHUSETTS, ASSIGNOR OF ONE-HALF TO
ALBERT E. PERRON, OF FALL RIVER, MASSACHUSETTS.

LEVER CHOCK.

Application filed April 30, 1923. Serial No. 635,738.

To all whom it may concern:

Be it known that I, OMER C. GOULET, a citizen of the United States, residing at Fall River, in the county of Bristol and State of Massachusetts, have invented certain new and useful Improvements in Lever Chocks; and I do declare the following to be a full, clear, and exact description of the invention, such as will enable others skilled in the art to which it appertains to make and use the same.

This invention relates to an improved device which may be conveniently referred to as a lever chock, the office of the device being to hold a rod shifting lever of a folding machine or the like in a set position.

It is the principal object of the invention to generally improve upon devices of this class by providing one which is practical, reliable and positive in action, and comparatively simple in construction.

More specifically speaking, it is an object of the invention to simply equip the usual lever mounting bracket with an integral ear which provides a shoulder, and to pivotally mount a supplemental lever or chock on the main lever for co-action with the shoulder to maintain the shifting lever in a set position.

Other objects and advantages of the invention will be apparent during the course of the following description.

In the accompanying drawing forming a part of this specification and in which like numerals are employed to designate like parts throughout the same:

Figure 1 is a perspective view of a portion of a well known type of folding machine showing the application of the lever chock to the belt shifting lever.

Figure 2 is an enlarged sectional view with parts in elevation, showing the construction more clearly, the chock being shown in operative position.

Figure 3 is a view similar to Fig. 2 showing the parts in their normal ineffective position.

Figure 4 is a detail elevation, with portions shown in section showing the association of the two levers more clearly.

In the drawings, the letter F designates generally a portion of a conventional type of frame on a well known folding machine. As is usual, a horizontal belt shifting rod

R is slidably mounted on the frame and is

reciprocated by movement of the lever L which is pivotally mounted on a bracket B secured to one leg of the frame. As is obvious, when the lever is rocked upon its pivot, the rod R is moved for shifting the belt A from one pulley P onto the adjacent pulley. As these parts and operation are well known, no further description thereof need be entered.

As before intimated, the invention resides in the association of unique means with the lever L for maintaining it in a set position when the belt is shifted onto the rigid driving pulley. The preferred means for accomplishing this result comprises a supplemental chock lever 1 provided between its

ends with a pair of spaced ears 2 having pivotal connection with a portion of the main lever L at points above its pivotal connection with the mounting bracket B. The

lower end 3 of the chock lever is substantially wedge-shaped and is adapted to be engaged with an integral lug or ear 4 carried by the aforesaid bracket. Specifically described, the lug 4 has its outer

edge 5 inclined to form a shoulder and the correspondingly inclined surface of the lower end 3 of the lever is adapted to be engaged therewith as seen in Fig. 3 to hold the belt shifting rod R in a stationary state.

So that the chock lever will be substantially automatic in engaging the shoulder, a coiled spring 6 is employed and exerts a yielding pressure against the intermediate portion thereof, the spring being housed in

a socket 7 carried by the main shifting lever. Specifically described, the lug 4 has its outer edge 5 inclined to form a shoulder and the correspondingly inclined surface of the lower end 3 of the lever is adapted to be engaged therewith as seen in Fig. 3 to hold the belt shifting rod R in a stationary state. So that the chock lever will be substantially automatic in engaging the shoulder, a coiled spring 6 is employed and exerts a yielding pressure against the intermediate portion thereof, the spring being housed in a socket 7 carried by the main shifting lever.

Assuming that the parts are in the position shown in Fig. 3, it will be noted that the lug 4 is received between the lower end 3 of the chock lever and the intermediate portion of the main belt shifting lever. If it is desired to retain the shifting rod in a set position, the hand gripping portions of

the two levers are grasped and the chock lever is rocked on its pivot to release its grip from the lug 4. Then the main lever is swung on its pivot until it assumes the approximate position shown in Fig. 2. At a predetermined time, the lower end of the chock lever will pass beyond the shoulder

5 of the lug and when it is released, it will swing into engagement with said shoulder and maintain the shifting lever in a set position. Inasmuch as the spring 7 will

serve to maintain the chock lever in place,

there is no chance of it becoming accidentally disengaged from the shoulder.

By carefully considering the description in connection with the drawings, persons 5 familiar with devices of this class will doubtless be able to obtain a clear understanding of the invention. Therefore, a more lengthy and detailed description is deemed unnecessary.

10 Since probably the best results may be obtained with the construction and arrangement herein shown and described, this is taken as the preferred embodiment of the invention. However, I wish it to be understood that minor changes coming within the 15 scope of the invention as claimed may be resorted to if desired.

I claim:

1. In combination, a lever mounting 20 bracket having an ear thereon forming a shoulder, a shifting lever pivoted on the bracket at a point beyond said shoulder, said lever having a socket, a spring in the socket, and a chock lever pivoted to the first

named lever, said spring exerting yielding 25 pressure against the chock lever so that it will automatically engage with said shoulder when the shifting lever is moved outwardly a predetermined extent.

2. A device of the class described comprising a lever supporting bracket having an integral ear on its upper side, the outer edge of said ear forming a shoulder, a rod shifting lever pivoted between its ends on said bracket at a point beyond the shoulder, said lever being provided with a socket in one side, a coiled spring arranged in the socket, and a chock lever pivoted between its ends on the first named lever at a point adjacent said socket, said ear being normally positioned between the levers, and the lower end of the chock lever being automatically engaged with said shoulder when the shifting lever is swung outwardly a predetermined extent.

30 In testimony whereof I have hereunto affixed my signature.

OMER C. GOULET.
